UNITED STATES PATENT OFFICE.

EDWIN J. FISHER, OF NEW YORK, N. Y.

MATCH-LIGHTER.

1,339,185.

Specification of Letters Patent. Patented May 4, 1920.

Application filed August 9, 1919. Serial No. 316,297.

To all whom it may concern:

Be it known that I, EDWIN J. FISHER, a subject of the King of Great Britain, and resident of the city of New York, Flushing, 5 borough of Queens, in the county of Queens and State of New York, have invented a new and Improved Match-Lighter, of which the following is a full, clear, and exact description.

10 This invention relates to a match lighter, and aims to provide a device whereby matches other than safety matches may readily be lighted.

It is well known that difficulty has been 15 experienced in providing a suitable type of match lighter because the usual match lighters, comprising a sandpaperlike surface, quickly become unsightly and are consequently discarded.

20 Particularly in hotels, stores, etc., it has been difficult to provide a suitable match lighter, so that patrons often scratch matches upon polished surfaces, wall paper, and other places, which results in the ruination 25 of the surface so used.

My invention relates to a match lighter which shall be so extremely simple as to be economical in manufacture, which can be placed anywhere and be an ornamentation, 30 and which can be utilized in the capacity of an advertising medium.

Reference is had to the attached sheet of drawings which illustrates my invention, and in which—

35 Figure 1 is an elevational view of my improved form of match lighter; and

Fig. 2 is a sectional view therethrough showing a slightly modified form of construction.

40 In these views like reference numerals designate similar parts and the reference numeral 1 indicates any convenient block of material, which is provided with a recess. At the base of this recess, advertising matter 2 may be inserted and sunk into such recess; and, preferably flush with the upper surface of the block of material, there is a plate of glass 3, upon the center of which a second plate of glass 4 is mounted. Or, 45 as is the case in Fig. 2, this raised portion, as indicated in this figure by the reference numeral 5, may form an integral part of

the plate 3. It will be noted that in both Figs. 1 and 2 the plate 4 of the raised portion 5 is provided with squared edges. 55

It will now be seen that upon taking a match 6 and placing the same adjacent the edge of the plate 4, or raised portion 5, and pressing downwardly, at the same time exerting a slight pull upon the match, the 60 match will be ignited by what might be termed a "snapping action."

It will be noticed that the construction presented includes a main plate 3 and an abutment 5 rigid upon the main plate and that this abutment has an upper or main face across which a match may be moved freely and this face terminates in an edge united by a face at an angle to said main face, the said edge being entirely unobstructed so that the match moved freely across the main face will be ignited by contact with said unobstructed edge in crossing the same. 70

Obviously, the construction illustrated 75 will at no time become unsightly, as any marks upon the surface of the glass may readily be removed by passing a damp cloth over the same. Further, the device could be used to great advantage with a view of displaying advertising matter, which might be printed as indicated by the reference numeral 2. 80

It will be understood that any number of modifications in connection with the mounting of the plate 4 or raised portion 5 might be resorted to without in the least departing from the scope of my invention, such as substituting in lieu of the block 1 a purely ornamental block, etc. 90

Having thus described my invention, I desire to claim:

A match igniter comprising a main plate and an abutment rigid upon the main plate, the abutment having an upper or main face across which a match may be moved freely, said face terminating in an edge united by a face at an angle to said main face, the said edge being entirely unobstructed, whereby a match moved freely across the 95 main face may be ignited by contact with the said edge in crossing the same, as and for the purposes set forth. 100

EDWIN J. FISHER.
